DESIGN FOR A LAMP

Frederick A. Harker, San Francisco, Calif.

Application March 4, 1946, Serial No. 127,085

Term of patent 3½ years

(Cl. D48—20)

To all whom it may concern:

Be it known that I, Frederick A. Harker, a citizen of the United States of America, residing at San Francisco, in the county of San Francisco and State of California, have invented a new, original, and ornamental Design for a Lamp, of which the following is a specification, reference being had to the accompanying drawing, forming a part thereof.

The figure is a perspective view of a lamp, showing my new design.

The characteristic features of my design reside in the portions shown by means of full lines in the drawing.

In the lamp, the cylindrical pedestal is transparent disclosing a floral vine entwined about a central rod.

I claim:

The ornamental design for a lamp, substantially as shown and described.

FREDERICK A. HARKER.
